A. S. Johnson
his Attorney

UNITED STATES PATENT OFFICE.

HERMAN H. PRETZEL, OF STILLWATER, MINNESOTA.

DESIGN FOR A GREASE-GUN.

51,817.

Specification for Design.

Patented Feb. 26, 1918.

Application filed April 2, 1917. Serial No. 159,343. Term of patent 14 years.

To all whom it may concern:

Be it known that I, HERMAN H. PRETZEL, a citizen of the United States, residing at Stillwater, in the county of Washington and State of Minnesota, have invented a new, original, and ornamental Design for Grease-Guns, of which the following is a specification, reference being had to the accompanying drawings, forming part thereof.

In the drawings,

Figure 1 is a perspective view of a grease gun, illustrating my new design.

Fig. 2 is an end elevation of the same.

I claim:

The ornamental design for a grease gun as shown.

HERMAN H. PRETZEL.
